(57) **CLAIM**

The ornamental design for an electric scooter, as shown and described.

DESCRIPTION

FIG. 1 is a perspective view of an electric scooter showing our new design;
FIG. 2 is a front view thereof;
FIG. 3 is a back view thereof;
FIG. 4 is an enlarged left view thereof;
FIG. 5 is an enlarged right view thereof;
FIG. 6 is an enlarged top view thereof;
FIG. 7 is an enlarged bottom view thereof; and,
FIG. 8 is a partially enlarged view of FIG. 5.
The broken lines shown on the drawings depict portions of the electric scooter that form no part of the claimed design.
